NOVELTY DEVICE

Filed Sept. 25, 1928

UNITED STATES PATENT OFFICE

ARTHUR SAMUEL DRUIFF, OF ATLANTA, GEORGIA

NOVELTY DEVICE

Application filed September 25, 1928. Serial No. 308,233.

Generically this invention relates to novelties, but it is more especially directed to the type of novelty whereby a pictorial representation may be made to present different 5 views by actuation of the device.

An important object of this invention is the provision of a frame for holding a photograph or other picture so constructed that pivotal actuation of the device varies the expression or perspective of the photograph or picture, thereby producing a fanciful effect.

A further object of this invention is the provision of a clamp-like frame having its 15 complementary sections curved to hold a photograph or other picture therebetween so as to present an uneven plane surface, whereby actuation of the device on its pivotal vertical axis changes and varies the expression or perspective of the picture to 20 present a variety of expressions or views to produce a fanciful or illusional result.

With these and other objects in view, which will become apparent as the description 25 proceeds, the invention resides in the construction, combination and arrangement of parts, hereinafter more fully described and claimed, and illustrated in the accompanying drawings, in which like characters 30 of reference indicate like parts throughout the several figures, of which:

Fig. 1 is a front elevation of the device, with the picture operatively positioned in the holder;

Fig. 2 is a side view of the device illustrated in Fig. 1; and

Fig. 3 is a view of the device partially open with the picture removed.

Briefly stated my invention consists in the provision of a frame having complementary hinged sections and means for securing the sections together in clamping relation with a photograph or other picture secured between the frame sections, the complementary sections 40 presenting correspondingly curved or uneven side edges whereby the picture when operatively positioned will present an uneven surface, said frame adapted to be constructed with a handle member projecting downwardly therefrom by means of which the angular

position of the frame may be changed to present a variety of continuously changing expressions or views of the picture being exhibited, and it was to produce such a result that I designed the device forming the subject matter of this invention. 55

In the illustrated embodiment characterizing this invention there is shown a frame member 5 substantially rectangular in the present instance and preferably formed from a one-piece wire having one end soldered or otherwise connected with itself as at 6, the free end of said wire extending downwardly to form handle 7, having its lower extremity curved inwardly upon itself as at 8 to form a rounded extremity, so that when desired the device may be easily and freely pivotally actuated on a suitable support, as will herein-after more fully appear. A complementary frame member 9 is hingedly connected to the member 5 in any well known manner as at 10, said member being an exact duplicate in shape and contour to that of member 5, having its inner end similarly connected as at 11 and a downwardly projecting member 12 in parallelism with handle 7, but being shorter in length, and adapted to be engaged by slip ring 13, slidably mounted on the handle 7 to maintain said members 5 and 9 in clamping contact with a picture 14 secured therebetween. 70 75 80

While I have preferably shown the sides of the frame as presenting a series of alternately oppositely extending curves, it is to be understood that the complementary frame members may be correspondingly formed of a different number of curves extending in different directions or partially or wholly zig-zag or otherwise, to present a further variation in expression or to further vary the changeability of the picture being exhibited without departing from the spirit of my invention. 85 90

From the above it is apparent that I have 95 designed a novel game or mirth provoking device whereby actuation of the device on its pivotal axis will present a variety of continuously changing expressions or views and which device may be employed with equal 100

facility as a fun producing, educational or advertising medium.

It will be further observed that the device is adaptable to a variety of uses, manufactureable at a negligible cost, simple in construction and efficient for the purposes intended.

Although in practice I have found that the form of my invention illustrated in the accompanying drawings and referred to in the above description as the preferred embodiment, is the most efficient and practical; yet realizing the conditions will necessarily vary, I desire to emphasize that various minor changes in details of construction, proportion and arrangement of parts, may be resorted to within the scope of the appended claims without departing from or sacrificing any of the principles of this invention.

Having thus described my invention, what I desire protected by Letters Patent is as set forth in the following claims:

1. A holding device embodying spaced pairs of interconnected complemental members, the members of each pair being formed with undulations throughout their lengths, a picture adapted to be inserted between the members, a handle connected with said device coincident with the median line between said pairs, whereby pivotal actuation of said handle effects optical distortional variations throughout the surface area of said picture.

2. A holding device embodying spaced pairs of complemental members, means interconnecting the upper and lower ends of the respective members of each pair, the members of each pair being formed with corresponding undulations throughout their lengths, a picture adapted to be inserted between the members with the pictorial representation intermediate said pairs, a handle means associated with the means interconnecting the lower ends of said members coincident with the median line between said members and of said picture, whereby pivotal actuation of said handle on its vertical axis coincident with the median line of said picture effects optical distortional variations throughout the surface area of said picture.

3. A holding device embodying a pair of frame sections, including side and end members, the side members of the respective sections adapted to receive a picture therebetween and formed with corresponding undulations throughout their lengths, means for detachably connecting the sections, and handle means associated with one end of the respective sections coincident with the median lines of the picture, whereby pivotal actuation of said handle on its vertical axis coincident with the median line of said picture effects optical distortional variations throughout the surface area thereof.

4. A holding device embodying a pair of hingedly connected complemental frame sec-

tions including side and end members, the respective side members being formed with corresponding undulations throughout their lengths and adapted to receive a picture therebetween with the pictorial representation bounded by the frame, a handle connected to the lower end of one of the frame sections centrally of its length, a complemental projection carried by the other section, and means for detachably connecting said handle and projection, whereby pivotal actuation of said handle on its vertical axis coincident with the median line of said picture effects optical distortional variations throughout the surface area of said picture.

5. A holding device embodying a pair of hingedly connected complemental frame sections, each of said sections formed from a one-piece rod bent to form end and side members, each of said side members being formed with corresponding undulations throughout their lengths, and adapted to engage the respective edges of a picture with the pictorial representation bounded by said sections, one of said sections terminating centrally of its lower end in a handle member, and means for detachably connecting said sections, whereby pivotal actuation of said handle on its vertical axis coincident with the median line of the picture effects optical distortional variations throughout the surface area of said picture.

ARTHUR SAMUEL DRUIFF.
